DESIGN FOR A HAT

Lulu A. Johnson, New York, N. Y., assignor to Hat Corporation of America, Norwalk, Conn., a corporation of Delaware

Application January 19, 1939, Serial No. 82,433

Term of patent 3½ years

To all whom it may concern:

Be it known that I, Lulu A. Johnson, a citizen of the United States, residing at New York, in the county of New York and State of New York, have invented a new, original, and ornamental Design for a Hat, of which the following is a specification, reference being had to the accompanying drawing, forming a part thereof, and in which:

Figure 1 is a perspective view of a hat embodying the design.

Fig. 2 is a side view of the hat shown in Fig. 1.

I claim:

The ornamental design for a hat, substantially as shown.

LULU A. JOHNSON.
